UNITED STATES PATENT OFFICE.

THOMAS GOODENOUGH, OF WOODSIDE, ASSIGNOR TO WILLIAM P. WARD,
OF NEW YORK, N. Y.

DOOR-CHECK.

SPECIFICATION forming part of Letters Patent No. 432,485, dated July 15, 1890.

Application filed September 5, 1889. Serial No. 323,081. (No model.)

To all whom it may concern:

Be it known that I, THOMAS GOODENOUGH, of Woodside, in the county of Queens and State of New York, have invented a certain 5 new and useful Improvement in Door-Checks, of which the following is a specification.

This invention relates to that class of door-checks known as "pneumatic door-checks," and it consists in the construction and novel 10 arrangement of parts, as hereinafter set forth.

The object is to provide a door-check which is simple and cheap in its construction and to so connect the piston-rod to the operating-lever that a door to which the check is attached may be swung back against the wall. 15

In the drawings, Figure 1 is a top view showing the position of the parts when the door is closed. Fig. 2 shows the position of the parts when the door is open, and Fig. 3 is 20 a front view with a portion of the cylinder broken away.

Similar letters indicate like parts in all the figures of the drawings.

Referring by letter to the drawings, A designates a cylinder having the head a, from 25 which extend arms a' a², provided with holes for the passage of screws to attach the device to a door-casing. A piston B is arranged within the cylinder and provided with a rod 30 b, extending through an opening in one of the cylinder-heads. A spring b' is coiled around the piston-rod in the rear of the piston, and a valve b² is seated in one head of the cylinder, by which the escape of compressed air may be regulated. 35

As the above parts are of the ordinary construction and operate in the usual manner,

further description thereof is not deemed necessary.

C designates the operating-lever pivotally connected to the arm a². I have here shown the arm a² as slotted and the end of the operating-lever pivoted therein.

The lever C is substantially S-shaped, and has a long curved bearing-surface c. The 45 lever has a swinging or sliding connection with the piston-rod b, consisting, as here shown, of a link D, pivoted at one end to the piston-rod, extending forwardly therefrom and embracing each side of the lever C, and having 50 a roller-bearing d within the outer end bearing upon the surface c of the lever C.

The lever C is pivotally connected at its outer end to one end of a link e', which is pivoted at its other end to the bracket e², secured to the door. 55

By connecting the lever C to the piston-rod by means of a swinging connection, instead of the rigid connection usually employed, I am enabled to swing a door farther open, as the 60 links being pivoted may be drawn out of line of the piston-rod, as shown in Fig. 2.

Having described my invention, what I claim is—

In a door-check, the combination, with the 65 cylinder, the piston, the piston-rod, and the curved actuating-lever, of the link pivoted at one end to the piston-rod and having a bearing against a curved surface of the actuating-lever, substantially as specified.

THOMAS GOODENOUGH.
